United States Patent [19]

Izaki

[11] Patent Number: Des. 314,188

[45] Date of Patent: ** Jan. 29, 1991

[54] **OPERATION ARITHMETIC CONTROLLER WITH MAGNETIC DISK FOR ELECTRONIC COMPUTER**

[75] Inventor: **Kenzo Izaki, Chiba, Japan**

[73] Assignee: **Kabushiki Kaisha Toshiba, Kanagawa, Japan**

[**] Term: **14 Years**

[21] Appl. No.: **344,021**

[22] Filed: **Apr. 20, 1989**

[57] **CLAIM**

The ornamental design for an operation arithmetic controller with magnetic disk for electronic computer, as shown and described.

DESCRIPTION

FIG. 1 is a front, top and right side perspective view of an operation arithmetic controller with magnetic disk for electronic computer showing my new design; FIG. 2 is an enlarged front elevational view thereof; FIG. 3 is an enlarged rear elevational view thereof; FIG. 4 is an enlarged top plan view thereof; FIG. 5 is an enlarged right side elevational view thereof; FIG. 6 is an enlarged left side elevational view thereof; FIG. 7 is an enlarged bottom plan view thereof; FIG. 8 is a front, top, and right side perspective view thereof, the lid of the operation panel being in the opened position.

FIG.1

FIG.2
